UNITED STATES PATENT OFFICE.

GEORGE W. UMSTEAD, OF UPPER SANDUSKY, OHIO.

EXCAVATING MACHINERY.

Application filed February 19, 1921. Serial No. 446,358.

My invention relates to excavating machinery, and in particular to ditching machinery.

The object of my invention is to provide a combined tractor and ditcher which may move to and from the job on which it may be employed under its own power and will utilize the same power for the ditching operations. It is an object of my invention to provide motive power which will drive the mechanism at varying road speeds and motive power which will drive the ditcher at varying speeds. It is also an object of my invention to provide a ditcher, the mechanism of which may be actuated for the adjustment of the several positions of the excavating and conveying machinery by the same source of motive power which actuates it to accomplish its other objects. It is an object of the invention to provide a ditching machine that will require the services of a single operator. It is an object of my invention to provide a ditching machine which the single operator may suitably direct so that the ditch will be made in conformity with the plane on which the ditch is laid out. Heretofore, it has been a source of difficulty that ditchers could not be kept upon the line of the ditch as it was laid out. My invention solves this problem. It is an object of the invention to provide a tractor with wheels which will be suitable for both road and field work. It is an object of my invention to provide interchangeable cutting members on the cutting or excavating wheel. It is further my object to provide a plurality of cutting members which will cut away successive and different portions of a ditch. It is an object of my invention to provide a self-cleaning cutting wheel. It is an object of my invention to provide a cutting wheel and an adjustable conveyor for delivering the material either into the ditch after the ditch has been excavated and the tile laid therein or to one side of the ditch, or upon a truck or trailer adjacent to the ditch. It is a further object of my invention to provide various improvements in the gear mechanism and in the gear shifting mechanism, as well as various improvements in the mechanism and method of operation of the ditcher proper, its positioning and elevation for transportation on the road, and its operation in the ditch. It is also an object to provide a source of power for turning by belt any auxiliary machines,

such as a sharpening machine, etc., for the cutting blades.

Referring to the drawings:

Fig. 1 is a plan view;

Fig. 2 is a side elevation of the ditching portion of the mechanism;

Fig. 3 is a sectional view of a part of the tractor mechanism;

Fig. 4 is a plan view partially in section of a bearing for certain shafts;

Fig. 5 is a section of a portion of the gear shifting mechanism;

Fig. 6 is a section of one of the cutting blades;

Fig. 7 is a section of the excavating wheel and a portion of the conveyor;

Fig. 8 is a section of one of the cutting blades;

Fig. 9 is a section of the cutting wheel;

Fig. 10 is a section of another of the cutting blades;

Fig. 11 is a detail plan of the conveyor with the cutting wheel in section;

Fig. 12 is a view of a part of the driving gear mechanism on the ditcher;

Fig. 13 is a detail section of the universal driving pulley of the conveyor;

Fig. 14 is an end elevation of Fig. 13;

Fig. 15 is a detail of the tension apparatus for the belt of the conveyor and the end pulley of the conveyor;

Fig. 16 is a section on the line *a—a* of Fig. 15 of the conveyor pulley;

Fig. 17 is a view of the tile laying mechanism;

Fig. 18 is a view of a portion of the bucket carrying wheel looking from above, the buckets being removed and the view disclosing the manner in which the scraper is supported.

Referring to the drawings, 1 is a frame of a tractor mechanism mounted on the axles 2 and 3 suitably supported on springs. The tractor is guided through the arms 4 and links 5 in any desired way by a hand wheel or other steering mechanism. In my preferred form the driving wheels 6 have mounted thereon a plurality of cleats 7 interconnected by links 8 and joined at 9 to make a non-skid arrangement on each of the driving wheels. This arrangement can be readily removed when it is desired to run upon the highways or ground where the broad tread is not necessary. 10 is any desired type of internal combustion engine. The source of power is immaterial. 11 is a

gear box in which there are located a plurality of gears operated by a plurality of control levers to be hereinafter described. The gear box is supported on cross members 12-12. 13 is the main power shaft which drives through suitable gearing, to be hereinafter described, the shaft 14, on which is mounted the pulley 15, the sprocket wheel 16 and the chain 17. This chain 17 is guided by the rollers 18 and 19 and engages with a sprocket wheel 20 on the shaft 21. 21 is a jack-shaft which drives a pinion 22. 22 meshes internally with an internal gear 23 carried on an excavating wheel 24. 24 is mounted on a shaft 25 that is journaled in the ditcher frame 26 at 27. This wheel 24 is encased on one side by a plate 28 which is carried on the shaft 25, and is prevented from rotation by reason of the passage through the plate of the shaft 21, the plate being thus a fixed member. The peripheral plates 29 on either side of the wheel forming the part of the casing are sloped inwardly, forming a dished wheel and rendering the construction very rigid. On the periphery of these dished members are located a plurality of cutting members. These members are of three kinds and are located in groups of 3, one of each kind being in a group. These cutting members are known successively at 30, 31 and 32 (see Figures 6, 8 and 10). It will be noted that in 30 there is a struck-up portion 33 which gives the final cut to the bottom of the ditch to provide a hollowed out place to center the tile to be laid in the ditch. The order in which the blades are located on the cutting or ditching wheel is 32, 31 and 30. These cutting blades are mounted on the periphery of the wheel 24 in any desired manner. There is a space 34 between the blades and the periphery of the wheel 24 between the dished members 28. In this space, at the top of the wheel, is a diverting member 36 that extends from the outer wall of 29 (see Figures 7 and 9) to the inner guard wall 27 adjacent the conveyor. This member 36 is supported by a rod 36^a which is secured in a socket 36^b on a frame member 83 hereinafter referred to. A scraper 38 is carried by and rotates with the wheel and passes through the slot 39 of the scraper 36. Means for loosening any accumulation of dirt is provided by the pin 40 passing through the slot 41 in 36. 40 is carried by 29. An additional scraper to remove the earth from the interior of the cutting members will be seen at 42 carried on the spring rod 43, which keeps the cutting head 42 up against the inside of each cutting member and scrapes therefrom the dirt so that it will drop down upon 35 and be conveyed away by 36 laterally on top of the conveyor belt 44. The conveyor belt 44 travels on the master driving pulley 45 which is actuated by the jack-shaft 21. The

outer end of this jack shaft is journaled in a bracket 46^a mounted on the frame 26 of the ditcher. The other end of the belt 44 is mounted on the tension pulley 47. This pulley is journaled on a shaft 48 that is carried by a yoke 49. This yoke 49 has interposed between it and the main supporting frame 50 a spring 51 that has the constant tendency to keep the belt 44 taut. A frame 52 supports the entire belt actuating and supporting mechanism. The belt is supported at intermediate points through brackets 53 and rollers 54 that are centrally supported by 50. The side walls to prevent the earth from falling off of the conveyor are formed by the frame 52.

The entire conveyor mechanism is supported by a bracket 55. This bracket passes through an eye 56 that has a suitable clamping mechanism 57 for positioning it in any desired position. 50 is pivoted at 58.

The spring 59 is hooked at 60 and to the fork 61. The fork 61 is pivoted at 62 and has its free end 63 pressing against the guard plate 64 that rests against the end of the driving pulley 45. This serves to keep the guard plate in position and also keep the guard plate against the end of the pulley as the conveyor swings. As the shaft 21 remains stationary and the pulley 45 must necessarily swing with the conveyor, it is essential to provide some form of universal joint.

This joint will be seen in Figure 13 in section. 21 is the shaft, 46 the driving gear and 45 the pulley. On the interior of this pulley is provided a ring 65 which is fixed to 45 by the pins 66. A collar 67 is fastened to the shaft 21. On the pin 68 the ring 65 is swiveled so that 45 can turn about the pin and change its position with respect to 21, assuming the various degrees of angularity to it and still be driven by it. Thus, as the conveyor swings from position to position, the shaft 21 will continue to drive 45.

This mechanism is seen in another view in 16 where there is a section taken on the line b-b of Figure 13.

In Figure 14 is an end elevation of 45 showing a slot 69 in the end plate 70 to permit of the free movement of the pulley with respect to the driving shaft 21.

In Figures 11, 12 and 13, will be seen a pin 71 carried by the sprocket 46. The sprocket 46 is carried between two plates 72 which are held together by 71. If the strain becomes too great upon 46 this pin 71 will be sheared so that the cutting wheel will cease to be driven and any jamming of the parts or obstruction in its road will not tear up the mechanism.

In Figure 11 will be seen the frame which supports the ditcher proper. Uprights 73 and 74 in the form of I-beams, act as

tracks for the rollers 75 carried by the bracket 76 on cross member 77. To this cross member 77 is pivoted at 78 an end frame member 79. The diagonal frame member 26 is fastened at 80 to 79 and at 81 to a lateral frame member 82. An intermediate frame member 83 is connected at 84 to 79 at one end and at the other end to 26 at 85. There is a cross brace 86 between 26 and 82. In 83 and 82 the shaft 25 of the ditching wheel 24 is journaled. Upon 82 is mounted the crank 87 that is connected at one end to a spring 88. This spring has one end connected to the crank 87 and the other end connected to a hook or other suitable fastening 89 on 26. The other end of the crank 87 carries a loop or strap 90 in which is journaled a pulley 91, around which a lifting cable 92 passes. This lifting cable has one end connected at 93 to the top of the vertical frame 73 and the other end passes over a pulley 94 journaled at 95 in 73. The cable 92 passes over 94 to the winding drum 96 and is actuated 25 through suitable gearing from the source of power 10 at the will of the operator through the gear shifting mechanism to be described later. This arrangement elevates the outer end of the ditcher frame. 30 The inner end is elevated through the cable 97 which is connected at 98 to the spring 99 that is in turn connected to the frame 73. This cable 97 passes around a pulley 100 carried on a bracket 101, mounted on the frame 35 of the ditcher. This cable 97 is wound on a drum 102 opposite the drum 96 found on the tractor frame. This serves to elevate the inner end of the ditcher frame and the mechanism carried thereby.

40 In order that the chain 17 may be properly directed and kept taut, there are a plurality of pulleys 18, 19 and 103 carried by the frame 73. The pulley 18 is maintained in its normal position by a spring or other resilient means so that it serves not only as a guiding element but also as a tightener to prevent any slack in the chain.

45 Beneath the frame 26 of the ditcher is a supporting member 104 that is braced by 50 105. It also acts as a support for 55. The bottom of 104 is supported on a trough-like member 106 that has the same cross section in general as the cutter 30. It travels along the bottom of the ditch and serves as a 55 vent spacer while the tile is being laid. It is preceded by a guard 107.

60 Referring to the tractor end of the ditcher 73, it is braced by 108 which is mounted on the frame 1 of the tractor.

65 As stated heretofore, this tractor has a plurality of cross members 12-12 which support the various gears and gear boxes. There is a main drive shaft 13 in this tractor which enters the gear box 11 to actuate a plurality of gears.

These gears are shown at 111 in Fig. 1 and constitute the change speed gears or transmission gears for driving the shafts 109 and 110 and are not necessary to be described in detail. The shaft 109 drives the tractor and 70 the shaft 110 drives the ditcher. The change gears are controlled by the rods 196 and 197 and rods 204 and 205 which may be operated by the control levers 184 and 185 in the usual manner. The shaft 109 drives the short 75 shaft 134 through the worm gearing 133 and this shaft 134 carries a bevel gear 136 which meshes with a bevel gear 137 revolvably mounted on a shaft 142. On the shaft 142 is splined a gear 140 which may be moved in 80 one direction to clutch engagement with the gear 137 or in the other direction to engage a gear 141 fixed on the shaft 109. By this means the shaft 142 may be made to revolve in one direction or the other with respect to the shaft 109. The shafts 109 and 142 are mounted in self alining bearings shown in Fig. 4 and hereinafter specifically described. A lever 147 serves to shift the gear 140 by means of a suitable connection 85 not deemed necessary to be described in detail. This shaft 142 drives the differential axle 3 through the differential gearing 156. The shafts 109 and 110 have like means for driving the respective drums 96 and 102, and the means for driving the drum 102 consists of a pair of bevel gears 163 and 164 loosely mounted on the shaft 110 but maintained in position by collars 165. There is a clutch member 166 which is shifted by a suitable 90 fork traveling in the groove 167. This clutch member has the usual clutch faces 168 cooperating with similar clutch faces on 163 or 164. 166 is adapted to slide laterally upon 110 but turns with it. 163 and 164 are 105 in mesh with the bevel gear 169 which is mounted on a shaft 170 that carries a suitable worm. This worm meshes with the worm gear 171 on a shaft 172 that carries the drum 102. 172 is supported by the 110 bracket 173. This shaft 110 also carries a bevel gear 175 which meshes with another bevel gear 176 carried by the jack shaft 14. This jack shaft 24 is journaled in the side frame of the tractor and carries the sprocket 115 16 which drives the chain 17. 14 also carries the pulley 15.

The steering of the vehicle is controlled by a hand wheel 209 which operates the steering shaft 210.

120 Referring to the self-aligning bearing, shown in Figure 4, there will be seen a supporting member 144 usually in the form of an angle iron, but this is not essential. In the upright portion of the angle iron 144 are 125 two apertures for the passage of the bearings and the shafts 142 and 109. A bearing 211 in the form of a long sleeve is placed over the shaft 109. A second bearing member 212 fits over 211 and has its exterior 130

tapered to fit in the aperture 214. A felt washer is slipped over 212 at 213 and embraced between 144 and a collar 215 which also surrounds 212 on the side opposite from that in which it was inserted. A clamp 216 retains the collar 215 in position, while a clamp 217 on the other side of 144 maintains the wedge-shaped collar 212 in position. The two clamps are held together by the bolt 218 which is positioned by the nut 219. It will be apparent that the shafts 142 and 109 may have a considerable degree of movement with respect to 144 and with respect to each other, but still be supported in proper bearings 211 and still be able to turn without friction so that as the tractor twists under various strains the shafts will not be likewise thrown out of alignment by the twisting of the supporting frame but will maintain their proper positions to perform their proper functions.

The wheels 6 have mounted thereon the endless tractor antiskid device consisting of a plurality of lateral members 7 joined together by links 8 which are attached by bolts 223 which are recessed in the apertures 224 and have heads 225. This chain of blocks or transverse members is held together by bolts 9 which are countersunk in the apertures 226 and 227. The nuts 228 serve to adjust the tension of this mechanism upon the tire 229 of the wheel.

The tile conveying mechanism 270 is composed of a pair of rods joined together by straps 271. The tiles slide down these guideways. The ends of the guideways are flattened at 272 so that they will lie close upon the bottom of the member 106. A roller 273 is carried by the arms 274 attached to 275 to support 276. The tiles are guided downwardly by the arms 270 beneath the roller 273 which prevents them from jumping off of the end of the tile conveying mechanism so that they will be delivered in an orderly manner into the bottom of the ditch.

Method of operation.

When the tractor or truck is moving along the road the ditcher portion of the mechanism is elevated. The speed of the tractor is determined by the shifting of the gears to the lever 184. The character of drive, whether worm or gear for the tractor, is determined by the shifting of the lever 147. The operator stands on the steps and operates these gears as well as steers the mechanism through the hand wheel 209.

When the work is reached, the stakes are laid out indicating the ditch and the job is ready to be started, the ditcher is lined up with the stakes so that the operator may look over the sighting rod 220 along this sight mechanism in line with the stakes, and may determine both his direction and depth of cut.

The ditcher proper is lowered by the unwinding of the cables 92 and 97 on their drums 96 and 102. The ditcher wheel is started in operation through the shifting of the lever 185 and the earth is thereby cut away, being elevated with the ditcher wheel and conveyed away by the conveyor either to one side of the ditcher or into the ditch after the tile has been laid by the tile layer heretofore described. This is at the option of the operator.

The ditching frame with its ditching mechanism is gradually lowered until the depth of the ditch as desired is reached. The tractor then can be thrown into gear and advanced slowly through the drive, principally the worm drive, so that the action of the ditcher is a progressive one along the line of the ditch as laid out.

While I have shown and described certain features as constituting my invention, it will be understood that parts have been shown for purposes of illustration only, and that I do not desire to be limited to such details, as obvious modifications will occur to a person skilled in the art.

Having thus fully described my invention, what I claim as new and desire to secure by Letters Patent, is:—

1. In combination an automotive vehicle driven by a source of power, a ditching means associated with said automotive vehicle, means carried by said automotive vehicle for bringing said ditching means in position for ditching, means associated with said automotive vehicle for regulating the position of the ditching means for ditching, said means consisting of independent agencies for controlling the respective positions of the outer and inner ends of said means for ditching, said means for supporting the inner end of the ditching means being adapted to support it in a plurality of positions, means regulating the movement of the automotive vehicle, means connected with said source of power on an automotive vehicle for actuating the ditching means, means for varying the speed of the ditching means, and means for varying the speed of the automotive vehicle.

2. In combination, an automotive vehicle driven by a source of power, a ditching means associated with said automotive vehicle, means carried by said automotive vehicle for bringing said ditching means in position for ditching, means associated with said automotive vehicle for regulating the position of the ditching means for ditching, means regulating the movement of the automotive vehicle, means connected with said source of power on an automotive vehicle for actuating the ditching means, means for varying the speed of the ditching means, and means for varying the speed of the automotive vehicle, said means located in a single

- housing having the mechanism therein driven from a common source of power and control means remotely located as a unit for controlling all of said means, said controlling means being adjacent to the operator and the ditching means, whereby the operator may observe the operation of the ditching means, the progress of the vehicle and still control the remotely located means for varying the speed of the vehicle and the speed of the ditching means, and means driven by the means to actuate the ditching means for conveying material excavated by the ditching means.
- 10 3. In combination, an automotive vehicle, a source of power mounted thereon, gear mechanism interposed between the source of power and the drive wheels for a plurality of speeds forward and a reverse speed, gear mechanism for a plurality of speeds for driving a ditcher integral with said automotive vehicle actuated by said source of power, a plurality of types of drive for actuating said automotive vehicle, said means located in a single housing having the mechanism therein driven from a common source of power and control means remotely located as a unit for controlling all of said means, said controlling means being adjacent to the operator and the ditching means, whereby the operator may observe the operation of the ditching means, the progress of the vehicle and still control the remotely located means for varying the speed of the vehicle and the speed of the ditching means, a ditcher, a frame for carrying said ditcher, a conveyor supported on said frame driven with said ditcher by said source of power, means connected with the outer end of said frame of the ditcher to the automotive vehicle adapted to be actuated by said source of power for lowering and elevating the outer end of the ditcher, a similar means for lowering and elevating the inner end of the ditcher frame, means on said automotive vehicle and said ditcher frame for permitting a relative adjustment of them with respect to one another and means connected with said ditcher frame for placing a conduit in said ditch, whereby a ditch may be excavated and a conduit laid therein.
- 15 4. In combination, a ditching wheel, means located internally of said wheel for actuating it, means to completely enclose said wheel to prevent material from entering said wheel from any direction, a plurality of cutting elements mounted on the periphery thereof, and means for dislocating material that adheres on the interior of said cutting elements.
- 20 5. In combination, a ditching wheel, means located internally of said wheel for actuating it, means to completely enclose said wheel to prevent material from entering said wheel from any direction, a plurality of cutting elements mounted on the periphery thereof, means for dislocating material that adheres on the interior of said cutting elements, and means for dislocating the material that adheres to said cutting wheel.
- 25 6. In combination, a ditching wheel, means located internally of said wheel for actuating it, means to completely enclose said wheel to prevent material from entering said wheel from any direction, a plurality of cutting elements mounted on the periphery thereof, means for dislocating material that adheres on the interior of said cutting elements, means for dislocating the material that adheres to said cutting wheel, and means for dislodging material adhering to said last mentioned means on the exterior of the wheel when said material is being removed therefrom.
- 30 7. In combination, a ditching wheel, means located internally of said wheel for actuating it, means to completely enclose said wheel to prevent material from entering said wheel from any direction, a plurality of cutting elements mounted on the periphery thereof, means for dislocating material that adheres on the interior of said cutting elements, means for dislocating the material that adheres to said cutting wheel, and means for dislodging material adhering to said last mentioned means on the exterior of the wheel when said material is being removed therefrom.
- 35 8. In combination, a supporting frame, a shaft journaled therein, an internal gear carried by said shaft and spaced therefrom, means to drive said internal gear, means to enclose said driving means and said internal gear on the sides and the periphery thereof, an outwardly flaring wall attached to the periphery of the wheel so formed, a plurality of cutting and elevating elements mounted on said upwardly and out-

wardly projecting wall, whereby as the gear is rotated the material may be excavated and elevated.

9. In combination, a supporting frame, a shaft journaled therein, an internal gear carried by said shaft and spaced therefrom, means to drive said internal gear, means to enclose said driving means and said internal gear on the sides and the periphery thereof, an outwardly flaring wall attached to the periphery of the wheel so formed, a plurality of cutting and elevating elements mounted on said wall, and means for removing material from said cutting and elevating means, whereby, as the gear is rotated, the material may be excavated and elevated.

10. In combination, a supporting frame, a shaft journaled therein, an internal gear carried by said shaft and spaced therefrom, means to drive said internal gear, means to enclose said driving means and said internal gear on the sides and the periphery thereof, an outwardly flaring wall attached to the periphery of the wheel so formed, a plurality of cutting and elevating elements mounted on said wall, means for removing material from said cutting and elevating means, and means for removing material that adheres to the periphery of the wheel so formed, whereby, as the gear is rotated, the material may be excavated and elevated.

11. In combination, a frame, a wheel journaled therein, an internal gear carried by said wheel, a pinion meshing on the interior of said gear, a drum on the periphery of said wheel and said gear, a plate to completely enclose one side of said wheel, a second plate to completely enclose the other side of said wheel and gear, said last mentioned plate remaining stationary with the frame but closely adjacent to said wheel and gear, means to drive said pinion, a guard wall on one edge of the periphery of said drum formed on the periphery of the wheel and a plurality of cutting and elevating members on the periphery of said wheel.

12. In combination, a frame, a wheel journaled therein, an internal gear carried by said wheel, a pinion meshing on the interior of said gear, a drum on the periphery of said wheel and said gear, a plate to completely enclose one side of said wheel, a second plate to completely enclose the other side of said wheel and gear, said last mentioned plate remaining stationary with the frame but closely adjacent to said wheel and gear, means to drive said pinion, a guard wall on one edge of the periphery of said drum formed on the periphery of the wheel, and a plurality of cutting and elevating members on the periphery of said wheel, said cutting members cutting in succession different portions of the ditch.

13. In combination, a frame, a wheel jour-

naled therein, an internal gear carried by said wheel, a pinion meshing on the interior of said gear, a drum on the periphery of said wheel and said gear, a plate to completely enclose one side of said wheel, a second plate to completely enclose the other side of said wheel and gear, said last mentioned plate remaining stationary with the frame but closely adjacent to said wheel and gear, means to drive said pinion, a guard wall on one edge of the periphery of said drum formed on the periphery of the wheel, a plurality of cutting and elevating members on the periphery of said wheel, and a guard wall on the periphery of said drum on the other side from the first mentioned guard wall, said second guard wall being stationary with the frame.

14. In combination, a frame, a wheel journaled therein, an internal gear carried by said wheel, a pinion meshing on the interior of said gear, a drum on the periphery of said wheel and said gear, a plate to enclose one side of said wheel, a second plate to enclose the other side of said wheel and gear, said last mentioned plate remaining stationary with the frame but closely adjacent to said wheel and gear, means to drive said pinion, a guard wall on one edge of the periphery of said drum formed on the periphery of the wheel, a plurality of cutting and elevating members on the periphery of said wheel, a guard wall on the periphery of said drum on the other side from the first mentioned guard wall, said second guard wall being stationary with the frame, and means carried on the drum for removing any material adhering to the last mentioned guard wall.

15. In combination, a frame, a wheel journaled therein, an internal gear carried by said wheel, a pinion meshing on the interior of said gear, a drum on the periphery of said wheel and said gear, a plate to completely enclose one side of said wheel, a second plate to completely enclose the other side of said wheel and gear, said last mentioned plate remaining stationary with the frame but closely adjacent to said wheel and gear, means to drive said pinion, a guard wall on one edge of the periphery of said drum formed on the periphery of the wheel, a plurality of cutting and elevating members on the periphery of said wheel, and a deflecting scraper supported on said frame and extending adjacent the drum and said side walls to remove material elevated on said drum.

16. In combination, a frame, a wheel journaled therein, an internal gear carried by said wheel, a pinion meshing on the interior of said gear, a drum on the periphery of said wheel and said gear, a plate to completely enclose one side of said wheel, a second plate to completely enclose the other

- side of said wheel and gear, said last mentioned plate remaining stationary with the frame but closely adjacent to said wheel and gear, means to drive said pinion, a 5 guard wall on one edge of the periphery of said drum formed on the periphery of the wheel, a plurality of cutting and elevating members on the periphery of said wheel, a deflecting scraper supported on 10 said frame adjacent the drum to remove material elevated on said drum, a dirt loosening device, and means in said deflecting scraper to permit of the passage of the dirt loosening device.
- 15 17. In combination, an automotive vehicle, a ditcher connected thereto, means on said ditcher for supporting in a plurality of positions the inner end of said ditcher, resilient means on the outer end of said ditcher for connection with a second supporting means connected to said automotive vehicle for supporting the outer end of the ditcher 20 yieldingly to conform to the variations of the position of the ditcher in said ditch.
- 25 18. In combination, an automotive vehicle, a frame therefor, a frame mounted at right angles thereto thereon consisting of a pair of upright I-beams spaced from one another, a ditcher frame having on either side thereof 30 of adjacent said I-beams a bracket for a pair of rollers traveling in the depressed portions of said I-beams on the opposite side of said I-beam and rollers traveling on opposite edges of one of the cross members of 35 said I-beam, said brackets and roller members being connected to one another by a cross member, a brace extending from said cross member upwardly and laterally to engage with one of the I-beams and rollers on 40 said brace engaging with said I-beam, a resilient means connected to said brace at one end and to the vertical frame at the other end for yieldingly supporting the guiding mechanism for the inner end of the ditcher 45 frame adjacent the automotive vehicle, whereby the ditcher frame may travel on the vertical frame of the automotive vehicle and be guided thereby.
- 50 19. In combination, an automotive vehicle, a frame therefor, a frame mounted at right angles thereto thereon consisting of a pair of upright I-beams spaced from one another, a ditcher frame having on either side thereof 55 of adjacent said I-beams a bracket for a pair of rollers traveling in the depressed portions of said I-beams on the opposite side of said I-beam and rollers traveling on opposite edges of one of the cross members of 60 said I-beam, said brackets and roller members being connected to one another by a
- cross member, a brace extending from said cross member upwardly and laterally to engage with one of the I-beams and rollers on said brace engaging with said I-beam, a resilient means connected to said brace at one 65 end and to the vertical frame at the other end for yieldingly supporting the guiding mechanism for the inner end of the ditcher frame adjacent the automotive vehicle, and a sighting means adjustably located upon 70 said brace, whereby the ditcher frame may travel on the vertical frame of the automotive vehicle and be guided thereby.
20. In combination, an automotive vehicle frame, a vertical frame thereon consisting 75 of a pair of I-beams spaced from one another, means to space said I-beams, a frame traveling thereon with rollers on said frame engaging with said I-beams to prevent lateral and transverse movement, a ditcher 80 frame connected to said cross frame, a support carried by said cross frame, a shaft carried by said support having a laterally projecting arm thereon, a guide roller on the end of said arm, a guide roller on the 85 main portion of said shaft, a second shaft on said support, a second guide roller thereon, a resilient means connected to the first shaft at one end and to the removable cross frame at the other end, whereby a flexible 90 means might be guided and kept taut by the rollers on said shaft as said frame moves vertically on said vertical frame.
21. In combination, an automotive vehicle frame, a vertical frame thereon consisting 95 of a pair of I-beams spaced from one another, means to space said I-beams, a frame traveling thereon with rollers on said frame engaging with said I-beams to prevent lateral and transverse movement, a ditcher 100 frame connected to said cross frame, a support carried by said cross frame, a shaft carried by said support having a laterally projecting arm thereon, a guide roller on the end of said arm, a guide roller on the 105 main portion of said shaft, a second shaft on said support, a second guide roller thereon, a resilient means connected to the first shaft at one end and to the removable cross frame at the other end, and a ditcher frame 110 connected thereto and resilient means for maintaining in an elevated position said cross frame with respect to said vertical guiding frame, whereby a flexible means might be guided and kept taut by the rollers on said shaft as said frame moves vertically 115 on said vertical frame.

In testimony whereof, I affix my signature.

GEORGE W. UMSTEAD.
